UNITED STATES PATENT OFFICE

120,911

DESIGN FOR A HORN HOUSING OR SIMILAR ARTICLE

Lyndon V. Grover, Los Angeles, Calif.

Application March 11, 1940, Serial No. 90,825

Term of patent 7 years

To all whom it may concern:

Be it known that I, Lyndon V. Grover, a citizen of the United States and a resident of the city of Los Angeles, in the county of Los Angeles and State of California, have invented a new, original, and ornamental Design for a Horn Housing or Similar Article, of which the following is a specification, reference being had to the accompanying drawing, forming a part thereof.

On the drawing:

I claim:

The ornamental design for a horn housing or similar article, as shown.

LYNDON V. GROVER,
